UNITED STATES PATENT OFFICE.

CARL E. MATHIESSEN, OF CHICAGO, ILLINOIS.

PENCIL-CASE.

SPECIFICATION forming part of Letters Patent No. 579,596, dated March 30, 1897.

Application filed November 27, 1896. Serial No. 613,685. (No model.)

To all whom it may concern:

Be it known that I, CARL E. MATHIESSEN, a citizen of the United States, residing at Chicago, in the county of Cook and State of Illinois, have invented a certain new and useful Improvement in Pencils, of which the following is a full, clear, concise, and exact description, reference being had to the accompanying drawings, forming a part of this specification.

10 My invention relates to a pencil having a movable lead. My object is to provide an improved construction of that type of pencil in which the lead may be moved longitudinally to project from the end of the pencil when in use and drawn into the casing when not in use.

In accordance with my invention the casing comprises a tube having a threaded bore, within which is placed a threaded traveler or 20 nut to which the end of the lead is attached, the traveler or nut being rotated to advance or retract the lead by means of a rotating cap or sleeve placed at one end of the casing and carrying a longitudinally-extending key 25 which engages the traveler in all positions of the latter.

I have illustrated my invention in the accompanying drawings, in which—

Figure 1 is a sectional view of a pencil embodying my invention. Fig. 2 is a detached view of the traveler. Fig. 3 is an end view of the traveler. Fig. 4 is a sectional view of a modification.

Like letters refer to like parts in the several figures.

The casing *a* of the pencil is provided with a threaded bore, within which moves a traveler or nut *b*, the periphery of which is threaded to engage the threads on the casing, whereby the traveler, when rotated, is caused to move longitudinally through the bore of the casing. Upon the traveler *b* is mounted a socket *b'*, in which the end of the lead *c* is clamped or otherwise secured, the opposite 45 end of the lead passing through the opening in the cap *d* on the end of the casing. Upon the opposite end of the casing is provided a

rotatable cap or handle *e*, and to this handle the ends of the parallel rods *f f'* are secured, the rods passing through holes in the traveler *b* and being secured at the opposite ends to a ring *f''*, which surrounds the lead *c*. 50

When the cap *e* is rotated to the right, the rods *f f'* engage and rotate the traveler *b*, causing the same to advance the traveler and move the lead forward to project from the end of the pencil. When the cap is rotated to the left, the traveler is caused to move in the opposite direction to move the end of the lead into the casing. 60

In Fig. 4 the cap *d*, through which the end of the lead is adapted to project, constitutes the rotating handle, the ends of the rods *f f'* being secured thereto, while the ring *f''*, to which the opposite ends are secured, is at the 65 opposite end of the casing.

Having described my invention, what I claim as new, and desire to secure by Letters Patent, is—

1. In a pencil, the combination with a casing having a threaded bore, of a traveler moving therein and having a threaded periphery to engage the threads of the casing, a mounting for the lead of the pencil provided upon said traveler, a rotatable handle at one end of 70 said casing, and a number of longitudinally-extending rods rotating with said rotatable handle and engaging said traveler to rotate the same, substantially as described. 75

2. In a pencil the combination with the casing *a* provided with the threaded bore, of the threaded traveler *b*, the mounting for the lead of the pencil provided thereon, the rotatable handle at one end of the casing, the rods *f f'* secured at one end thereto and the ring *f''* to 85 which the opposite ends are secured, substantially as described.

In witness whereof I have hereunto subscribed my name this 17th day of November, 1896.

CARL E. MATHIESSEN.
